OTHER PUBLICATIONS

Chipman et al., Design U.S. Appl. No. 29/714,715, entitled "Trash Receptacle", filed Nov. 25, 2019.

Primary Examiner — Cynthia Ramirez

(74) Attorney, Agent, or Firm — Heslin Rothenberg;
Farley & Mesiti P.C.(57) **CLAIM**

The ornamental design for a trash receptacle, as shown and described.

DESCRIPTION

This application is related to commonly assigned, co-pending design patent application Ser. No. 29/714,715, filed on Nov. 25, 2019 by Chipman et al. and entitled "Trash Receptacle", which application is hereby incorporated herein by reference in its entirety.

FIG. 1 is a perspective view of a trash receptacle in accordance with the new design;

FIG. 2 is a front elevational view thereof, a rear elevational view being a mirror image thereof;

FIG. 3 is a right side elevational view thereof, a left side elevational view being a mirror image thereof;

FIG. 4 is a top view thereof; and,

FIG. 5 is a bottom view thereof.

The broken lines in the drawings illustrate portions of the trash receptacle which form no part of the claimed design.
